Roman Kopanski, Cleveland, Ohio, assignor to
The Ward Products Corporation, Cleveland,
Ohio

Application September 13, 1937, Serial No. 71,601

Term of patent 3½ years

To all whom it may concern:

Be it known that I, Roman Kopanski, a citizen of the United States, residing at Cleveland, in the county of Cuyahoga and State of Ohio, have invented a new, original, and ornamental Design for an Automobile Roof Aerial, of which the following is a specification, reference being had to the accompanying drawing, forming part thereof.

In the drawing,

Fig. 1 is a side elevation of my new automobile roof aerial design;

Fig. 2 is an enlarged elevation of the same; and
Fig. 3 is a top plan view of the same with part broken away.

I claim:

The ornamental design for an automobile roof aerial, as shown.

ROMAN KOPANSKI.
